E. A. WOOD.
BOILER FEEDER FOR STEAM ENGINES.

No. 29,028.

Patented July 3, 1860.

Inventor,
E. A. Wood

UNITED STATES PATENT OFFICE.

EDWIN A. WOOD, OF UTICA, NEW YORK.

BOILER-FEEDER FOR STEAM-ENGINES.

Specification of Letters Patent No. 29,028, dated July 3, 1860.

To all whom it may concern:

Be it known that I, EDWIN A. WOOD, of the city of Utica, in the county of Oneida and State of New York, have invented a new and useful improvement or attachment to steam-boilers for the purpose of feeding the boiler and also of indicating when the pump or the hydrant has failed to perform its duty.

10 The nature of my invention consists in the regulating and controlling the pump or the hydrant and the alarm whistle by means of the height of the water in the boiler and by the expansion and pressure of steam.

15 Various modes may be adopted by which this can be effected. The simplest, safest and the most economical mode will be to use a reservoir at a short distance from the boiler, but connected with it by two tubes

20 or pipes, one of which tubes or pipes must enter the boiler at a point below low water mark of the boiler, and the other at a point above high water mark in the boiler; by means of which the lower part of the reservoir

25 is always filled with water to the same level as the boiler; and the upper part of the reservoir with steam. On the top of the reservoir is a steam cylinder with a piston and piston rod. On the underside of the

30 cap of the reservoir are openings for the steam to pass to the cylinder and the alarm whistle, which are covered by a common sliding valve, moved by a lever; which lever is moved by a hollow copper ball or float

35 attached to the long arm of such lever; which ball or float rests in the water of the reservoir. When the water in the boiler, and of course in the reservoir also, is of the proper height, the float rises which allows

40 the lever to rise also and the valve with them which covers and closes both of the post holes or openings for the passage of steam to the cylinder and the alarm whistle. And when the water lowers in the boiler and of

45 course in the reservoir, then the float sinks and by its weight, it draws down the lever and the valve attached thereto, and opens the port hole or opening to the passage of the steam from the boiler and reservoir to

50 the cylinder and the expansion and pressure of the steam in the cylinder raises the piston rod. To the upper end of the piston rod, is attached a cord chain or strap, which, by passing under a pulley attached to or near

55 the cylinder head, causes the belt shipper to pass the belt from the loose to the fast

pulley and thus put the pump shaft in motion, or open the valve of the hydrant. When the boiler becomes filled to a proper level and of course the reservoir also, the float rises with it and of course causes the sliding valve to rise and cut off the steam to the cylinder. A counterweight attached to the other side of the belt shipper draws back the belt to the loose pulley and the pump stops, 60 while the valve being hollow, in the usual form, allows the steam remaining in the cylinder to escape through the alarm whistle opening. The cylinder being small, and of course the quantity of steam remaining 65 therein is small; and as it escapes gradually no alarm is sounded by the whistle in its passage. If a hydrant is used for supplying the boiler the valve of the hydrant is opened by attaching the cord thereto, or by 70 any other proper contrivance; and such valve is closed when the piston ceases to act on the cord, by a weight or spring, or the pressure of the water of the hydrant. If the pump or the hydrant fails to perform its 75 duty when the steam is let into the cylinder as hereinbefore described, the water in the boiler and reservoir of course becomes lower and the float and lever and valve descend lower, until the port hole or opening of the 80 passage for the steam to the whistle is opened, when such alarm whistle is sounded. The length of the rods connecting the lever and the float determine the time when the pump or the hydrant valve must start and 85 also the height of the water to be let into the boiler; and by varying the length of the rods, the water lines of the boiler and reservoir are also varied.

The following is a full and exact description of the said boiler feeder, reference being had to the accompanying drawings, and to the letters of reference marked thereon, making a part of this specification, in which—

Figure 1 is a perspective view of the said boiler feeder; Fig. 2 is a sectional view of the same, together with the mode of connecting the same with the common belt shipper over the tight and loose pulleys for driving the pump; and Fig. 3 is a perspective view of the projection on the under side of the cap (half of the cap being removed) containing the valve seat, the port holes or opening therein and the sliding valve, together with the lever by which the same is moved. Fig. 4, on the second sheet, repre-

sents an enlarged perspective view of the said projection on the under side of the cap, containing the valve seat and the port holes or steam passages therein, the cap valve, and 5 lever being removed. Fig. 5 on the said second sheet is a perspective view of the said sliding valve, showing its under hollow surface. Fig. 6 on said second sheet is a sectional view of the upper end of the steam 10 cylinder showing more fully the piston and the valve seat thereof in the upper end of said cylinder.

A represents the reservoir; B, B² the tubes or pipes leading from the boiler to the reservoir; C is the cap or cover of the said reservoir; D, a projection on the underside of the cap; E is the sliding valve; F is the port hole or opening and F² the steam passage (marked by dotted lines) leading from the 20 cylinder; F³ is the port hole or opening and F⁴ is the steam passage (marked by the dotted lines) leading from the valve seat to the alarm whistle and which last mentioned passage F⁶ also serves as the exhaust passage 25 of the cylinder.

G is the lever for moving the valve E; and is connected with such valve E by the stirrup or connecting rod H.

I, I² are two rods by which the float is 30 suspended from the lever G; which rods are connected in the center by the movable coupling K, by means of which the height of the water in the boiler may be regulated; and L is the hollow copper ball or float. 35 The dotted line M, running across A and L, Fig. 2, is the level of the water in the reservoir, when the pump or hydrant commences to act.

N, is the cylinder; O is the piston; P P² 40 is the valve seat of said piston at the top of the cylinder; Q is the piston rod; S the cord or chain connecting the top of the piston rod with the belt shipper.

T, is the pulley attached to the cylinder 45 under which such chain or cord passes and T², another pulley over which the chain or cord passes; U is the belt shipper; V, V², are the tight and loose pulleys for driving the pump and U is the shaft to which the 50 pump is attached by a crank or otherwise.

X, is a counterweight to draw back the belt shipper after the steam is cut off from the cylinder; which said counterweight is attached to such belt shipper by a cord S² 55 and passes over a pulley T³ and Y is the alarm whistle.

The reservoir A, and the hollow copper ball or float L may be in the usual form of similar contrivances for water gages and 60 water indicators. The reservoir and cylinder must be of sufficient strength to resist the pressure of the steam of the boiler; and they may be of cast iron, brass or other suitable material. The reservoir may be cast in 65 any shape and closed at the lower end, with

a faucet for drawing off the water or cleaning out the sediment. The cap may be screwed on, or bolted on by means of flanges on it, and on the top of the reservoir, with the usual packing; the tubes B, B² may be 70 of the usual form and material of similar pipes or tubes used for water gages or indicators. B² must be connected with the boiler at a point below low water mark in the boiler and B at a point in the boiler above 75 high water mark; by means of which the water of the boiler passes freely into the reservoir at all times and will at all times remain at the same level therein, as in the boiler; but by reason of the reservoir being 80 detached from the boiler and only connected by the tubes, the water in such reservoir will be more quiescent and will not be subject to ebullition and foaming like the water in the boiler and hence perhaps the 85 boiler feeder may operate with more certainty if a reservoir is used, than if the cylinder and other parts were placed in and on the boiler itself. The upper tube B keeps the upper part of the reservoir supplied 90 with steam from the boiler.

The cylinder N, is an ordinary steam cylinder. It is screwed to the cap, or it may be attached to it in any way in which it may be made tight and secure and for the better 95 arrangement of all the parts should be placed at one side of the cap, as seen in Figs. 1 and 2. It is open at the top, but has a valve seat P, P² to which the upper side of the piston is fitted, as well to prevent the 100 leaking of steam, as the piston from being driven out of the cylinder by the steam.

The piston O and the piston rod Q, are in the usual form, except, as stated, the said piston O is fitted on the upper side to the 105 valve seat P, P². Across the top of the cylinder N is the cross piece R, screwed or otherwise attached thereto, through which the piston rod passes, and acts as a guide for such piston rod.

The projection D is a part of the cap, on the under side thereof. In this is the valve seat D² Fig. 4, with its dovetailed grooved sides to hold the valve E in place, and the port holes and passages F, F', F³ F⁴ leading 115 from the valve seat to the cylinder and alarm whistle, through the caps. The said valve seat is on the side of D and the valve E is an ordinary sliding valve, hollow on the under side or face, like the common 120 valve, attached to the lower extremity of D is the fulcrum of the lever G; which lever is connected with the valve E, by the stirrup or connecting rod H and the float is connected with the other arm of the lever by 125 the rods J, J². These rods are connected in the center by passing them through the movable coupling K and are fastened at the desired point with a set screw; or in any other 130 of the usual modes.

On the top or side of the cylinder N and at one side, is a small pulley T under which the cord or chain S, which is attached to the top of the piston rod, passes.

5 The alarm whistle may be of any of the common forms.

The method of operating the belt shipper by means of the chain or cord, has already been described; as well as the whole operation of the boiler feeder.

10 The size of the boiler feeder will depend upon the size of the boiler to which it is to be attached; but for boilers up to thirty horse power, there need be no variation.

15 For such size, the reservoir should be about fourteen inches in length, and about five inches inside diameter, with a float of from three and a half inches to four inches in diameter. The steam cylinder should have

20 a piston of about two inches in diameter, with a four inch movement. The port holes should be about one quarter of an inch in

their horizontal length and one eighth in width and the web between them should be about three thirty seconds of an inch. The 25 valve will work best in a dovetailed groove fitted to allow for expansion.

The advantages of this method of feeding the boiler are; certainty of performance, regularity in performance, safety, simplicity and economy.

30 What I claim as my invention and desire to secure by Letters Patent is—

1. The arrangement of the float L, cylinder N and piston O, constructed and operating as described, in combination.

35 2. The said float, cylinder and piston constructed and operating as described, in combination with the alarm whistle.

EDWIN A. WOOD.
